UNITED STATES PATENT OFFICE.

ANNIE M. YOUNG, OF PROVIDENCE, RHODE ISLAND, ASSIGNOR OF ONE-HALF
TO ABBY C. SMITH, OF BOSTON, MASSACHUSETTS.

GLOVE.

SPECIFICATION forming part of Letters Patent No. 410,999, dated September 10, 1889.

Application filed May 13, 1889. Serial No. 310,611. (No model.)

To all whom it may concern:

Be it known that I, ANNIE M. YOUNG, of Providence, county of Providence, State of Rhode Island, have invented certain new and useful Improvements in Gloves, of which the following is a specification, reference being had to the drawings accompanying and forming a part hereof, in which—

Figure 1 is a perspective view of my improved glove on a hand. Fig. 2 is a plan view of the pattern of the chief piece used in the manufacture of my improved glove. Fig. 3 is a plan view of the corresponding piece used in the manufacture of gloves as now made. In the manufacture of tight-fitting gloves from kid or other similar material a large number of sizes require to be made to suit the requirements of the trade, and this renders it necessary for retail and other dealers to carry very large stocks of gloves. This might be avoided by lessening the number of sizes; but with the accuracy of fit now required and the style of gloves as at present made it is impossible to lessen the number of sizes and give satisfaction to customers. As at present made, so far as known to me, tight-fitting gloves, especially ladies' kid gloves, are subjected to great strain across the hand near the base of the thumb just below the opening in the glove, and this strain very frequently results in starting the glove at that point—that is, cracking the material or slightly tearing it—while below that point—that is, in the palm of the hand—the same glove will be comparatively slack and will have, if anything, too much material. This same tightness of the glove across the hand at or near the base of the thumb is the cause of considerable loss to glove dealers, inasmuch as purchasers of gloves frequently insist upon having their gloves fitted to them by the dealer, and in putting them on they are always stretched at this point, and should either of the pair of gloves be strained or be otherwise unsatisfactory, that particular pair of gloves must be laid aside by the dealer, to be sold, if they can be sold at all, at an inferior price. The number of gloves thus damaged is often reckoned as high as one pair in every dozen. To avoid these objections and produce a glove which may with a less number of sizes

be fitted to any hand, as also one which may be tried on without danger of damaging it, and which also may be made to fit more accurately around the palm of the hand than has hitherto been possible, so far as I know, are the chief objects of my invention.

I have shown my invention as embodied in a ladys' kid glove, and I will describe the same, using letters of reference to the accompanying drawings.

The thumb and fingers of my glove are the same, substantially, as in gloves as now commonly made. The hand portion of the glove A, as also the backs and fronts of the fingers, 65 are, as in kid gloves as at present usually made, formed in one piece. The shape of said piece when flat and as cut from the material being for my improved glove of the shape shown, Fig. 2, and being for gloves as now 70 commonly made of the shape shown in Fig. 3. It will be noted that the difference between said piece in my improved glove and the corresponding piece as now used consists in cutting out of the piece which is used to make 75 my improved glove a peculiar tapering and substantially lance-shaped portion B, extending from a point near the base of the fingers and gradually widening past the thumb-hole C and extending with substantially parallel 80 sides toward the opening at the top of the glove. The exact shape of this piece is not essential, although it cannot be varied substantially in gloves adapted for hands of normal shape, and for kid gloves it is preferably 85 of the shape shown. The shape of the piece B and the amount of material removed should be such that when the glove is laced on the hand of the wearer the two edges of this opening should meet, or substantially meet, 90 throughout the whole or nearly the whole length of the opening in order to present a neat appearance and not show the flesh of the hand.

The tapering piece, which is cut from the pattern of my improved glove, may also be 95 utilized and is of some slight value, so that the first cost of the material is no greater than in gloves as now made, in which none of the material is cut out, but only a slit is made, as shown at D, Fig. 3, beginning at a point opposite the thumb-hole and extending to the top 100 of the glove.

In finishing my glove any of the well-known fastenings may be employed; but I prefer for the best results to lace the opening, as shown, Fig. 1, providing eyelets for that purpose on either side of the opening, from the lower or finger end thereof to a point opposite the thumb, and lacing studs or hooks from that point to the top of the glove. These eyelets may of course be covered and concealed, and the sewing and other features of the glove may be varied, as in the various styles of gloves now made.

By this construction quarter-sizes of gloves may be avoided, the same accuracy of fit which is now obtained by the manufacturer of full, half, and quarter sizes being obtainable in my improved gloves by the manufacture of full and half sizes only. In this way the stock of gloves now necessarily carried by dealers may be very largely reduced without producing dissatisfaction among customers. Such a glove, it will be clear, may also be tried on the purchaser and its fit ascertained without distorting or breaking the glove or diminishing its value to a subsequent purchaser.

It is also possible with my improved glove to fit a hand of abnormal shape with great accuracy by varying the shape of the piece B and thus varying the shape of the opening.

As the back of the hand is the part most difficult, as also most desirable, to have the glove fit accurately, my improved glove is particu-

larly adapted to accurately fit the back of the hand, as if at any point there is a slight fullness or looseness it may be taken up by the lace. It is also true that the palm being in my glove, as it were, adjustable or capable of being taken up by the lace, a glove of less size may be worn if made according to my improvement. This feature is important since it materially cheapens the cost of producing the glove.

I am aware that gloves have been previously made having long slits or openings to allow the hand to be inserted, as in loosed-fitting gloves designed for special purposes, which have been slit up the back and laced, and I do not broadly claim a glove having an opening from a point near the base of the fingers to the top.

What I do claim is—

A glove constructed with an opening in the palm portion from near the base of the fingers to the top, with means for closing the same, said opening being formed by the removal of a piece of the material, whereby the fullness of the glove in the palm of the hand is removed and the strain of the material opposite the thumb is obviated, substantially as shown and described.

ANNIE M. YOUNG.
